UNITED STATES PATENT OFFICE.

JOHN P. NISSEN, OF PHILADELPHIA, PENNSYLVANIA.

SWEATER.

Application filed May 3, 1924. Serial No. 710,895.

The present invention relates to improvements in sweaters or knitted jackets, and the object is to provide an improvement in the form of a combined collar and hood, which 5 does not change the normal appearance of the sweater or jacket when the collar is in its usual position. At the same time a hood is secured which will fit over and effectively cover the head of the wearer, leaving his 10 face exposed and yet binding snugly though comfortably about the face.

The preferred embodiment of the invention is illustrated in the accompanying drawings, wherein:—

15 Figure 1 is a perspective view of a portion of a sweater with the collar in its "lay-down" or usual position,

Figure 2 is a similar view of the hood in operative position on the head of the wearer,

20 Figure 3 is a detail perspective view showing the collar raised with the hood in its folded position,

Figure 4 is a view similar to Figure 3, but showing the hood piece partly turned 25 to its operative position,

Figure 5 is a vertical sectional view through the hood when in its operative position, as illustrated in Figure 2.

Figure 6 is a detail sectional view through 30 the collar and hood piece when in the position illustrated in Figure 1.

In the embodiment disclosed, the sweater or jacket may be of the usual construction, comprising a knitted body 7 with knitted 35 sleeves 8. Carried by the top of the body 7 is a collar, preferably composed of a central upwardly flared knitted section 9 with rows of loops running vertically, and side sections 10 composed of rows of loops running horizontally. This collar, as illustrated 40 in Figure 1, normally lies flat over the upper portion or back of the body 7 but can be elevated as illustrated in Figure 2 around the neck and rear portion of the head of the wearer. Its rear margin is formed on a generally convex curve as shown at 11.

Carried by this collar 9—10 is a hood piece designated generally by the reference numeral 12. The hood piece has a generally 50 convexly curved outer margin 13 corresponding to the curved margin 11 of the collar and suitably seamed thereto. The inner margin of this hood piece is straight and is designated 14. The hood piece is of 55 knitted material and the margin 14 is also formed of knitted material, the yarn thereof

being preferably of finer quality than the body portion 12 and of smaller loops, making an elastic binding. Preferably the inner 60 face of the hood piece is of fleecy material but the outer portion corresponds generally in color and form to the collar, as shown in Fig. 2.

When the collar is in its "lay-down" position upon the back of the body, as shown 65 in Figure 1, it completely overlies and hides the hood piece, said hood piece, as will be clear by reference to Figure 6, being doubled or looped beneath the collar. The sweater or

jacket thus has a normal appearance. When 70 it is desired to use the hood the collar is swung upward, as illustrated in Figure 4.

The free margin of the hood piece is then 75 available and can be turned upwardly over the head where it will assume the position shown in Figure 2. A button 15 on one side of the collar and a loop 16 for receiving the same on the other side of the collar at the ends of the hood piece serve to secure the hood snugly beneath the chin. Due to the 80 form of the collar and hood piece and the curved margins of the two parts which are secured together the hood will fit properly over the head and the elastic margin 14 will draw the free edge of said hood inwardly 85 so that it will fit about the face of the wearer, as shown in Figures 2 and 5.

From the foregoing, it is thought that the construction, operation and many advantages of the herein described invention will 90 be apparent to those skilled in the art without further description and it will be understood that various changes in the size, shape, proportion and minor details of construction may be resorted to without departing 95 from the spirit or sacrificing any of the advantages of the invention.

What I claim is:

1. The combination with a knitted jacket and a knitted collar carried thereby and adapted to lie over the back of the jacket or be raised about the wearer's neck, of a hood piece carried by the underside of the collar and overlaid by the same when the collar is in its lower position, said hood piece having its outer margin secured to the collar and its inner margin free therefrom and terminating at points in rear of the body of the jacket, and said inner margin being formed of elastic material that will 100 effect a close fit about the face of the wearer when the collar is raised and the hood piece 105

110

is placed over the head of the wearer, and means on the outer margin of the collar at the juncture of the ends of the hood piece, with said collar and at points removed from 5 the juncture of the collar with the body of the jacket for detachably fastening together beneath the chin, the collar and ends of the hood piece.

2. The combination with a knitted jacket 10 and a knitted collar comprising a central, upwardly flared knitted central section and side sections connected to opposite sides of the same, with the lines of loops in angular relation to those of the central section, of 15 a hood section extending across the outer end of the central section and connected to the outer margin of the same, said hood section having tapered end portions secured to the outer portions of the side sections, said hood 20 piece conforming to the shape of the head and having a face-surrounding free margin of finer knit than the main portion, and means at the juncture of the tapered ends of the hood section with the side sections 25 for detachably securing together said portions beneath the chin of the wearer.

3. The combination with a knitted jacket and a knitted collar carried thereby and comprising a central upwardly flared knitted central section, and side sections knitted thereto, said collar having a convexedly curved rear edge, of a hood section extend-

ing straight across the outer free portion of the collar and having a convexedly curved rear edge corresponding to and secured to 35 the rear edge of the central and side sections of the collar, said hood section having a substantially straight inner edge free from and extending across the collar sections between their inner and outer edges.

4. The combination with a knitted jacket and a knitted collar carried thereby and comprising a central upwardly flared knitted section, and side sections knitted thereto, 45 said collar having a convexedly curved rear edge, of a hood section extending straight across the outer free portion of the collar and having a convexedly curved rear edge corresponding to and secured to the rear edge of the central and side sections of the collar, 50 said hood section having a substantially straight inner edge free from and extending across the collar sections between their inner and outer edges, said hood section tapering to substantially terminal points, and means at said points and on the outer edge 55 of the collar in spaced relation to the body of the jacket for securing the ends of the hood piece together beneath the chin of the wearer.

In testimony whereof, I affix my signature.

JOHN P. NISSEN.
